Attorney

UNITED STATES PATENT OFFICE

BERNICE EARL LAMBERT, OF COLUMBUS, OHIO

SEALING MEANS FOR BURIAL CASKETS

Application filed November 25, 1927. Serial No. 235,582.

This invention relates broadly to improvements in receptacles, and more particularly to receptacles of the type embodying two separable sections, and the primary object 5 of the invention resides in the provision of a method and means for sealing the sections of such a receptacle together in order to positively exclude the elements and to preserve indefinitely the contents of the receptacle. 10 The invention is especially directed to receptacles in the form of burial cases, caskets, or vaults, although the scope and application of the invention are not, of course, limited to this specific field of employment, as the principles of the invention are applicable with 15 equal force and effect to receptacles employed for many other widely different uses and purposes.

In accordance with the present invention 20 there is provided a metallic receptacle consisting of a base section and a cover section, the base section being provided along its upper edge with an inturned substantially horizontally extending flange in which is 25 formed a substantially continuous channel extending around all four sides of the base section, the cover section, in turn, being arranged to rest upon said flange and is provided with a depending web which is adapted 30 to be positioned in the continuous channel provided in the base section, and means being provided in connection with said channel, following the association of the sections of the receptacle, to introduce preferably a 35 bituminous sealing compound into said channel so as to completely fill the same and to surround the web depending from the cover section, whereby upon the subsequent cooling and hardening of the sealing compound 40 a secure union will exist between the sections of the receptacle and, in addition, hermetically sealing the interior of the receptacle so that the latter will be unaffected by extraneous conditions and the contents thereof in- 45 definitely preserved.

With these and other objects in view that will appear as the description proceeds, the invention consists in the various steps of operation and combination and arrangements of parts hereinafter fully described 50 and set forth in the appended claims.

In the accompanying drawing:

Figure 1 is a plan view of a receptacle constructed in accordance with the present invention, a portion thereof being broken away 55 to disclose underlying structure,

Figure 2 is an enlarged vertical transverse sectional view taken on the line 2—2 of Figure 1,

Figure 3 is a detail sectional view disclosing 60 a slightly modified form of support for retaining a transparent panel in connection with the cover section of the receptacle,

Figure 4 is a similar view disclosing a modified form of the invention wherein the 65 web is carried by the flange of the base section,

Figure 5 is a horizontal sectional view disclosing more particularly the method and means employed for introducing the bituminous sealing compound in the channel provided in the base section of the receptacle. 70

Referring more particularly to the drawing the numeral 1 designates a receptacle constructed in accordance with the features 75 of the present invention. In the present instance the receptacle has been shown in the form of a sheet metal burial case or casket, inasmuch as the features of the present invention may be readily developed as claimed 80 by specifically setting forth the construction of the casket or case but I, of course, do not confine myself to this particular adaptation of the invention.

The case or receptacle comprises broadly a 85 base section 2 and a separable cover section 3, the base section comprises a bottom 4, vertically upstanding side and end walls 5 and 6 respectively and an open top. In this instance the upper edges of the walls 5 and 6 90

are welded or otherwise secured to an outwardly curving trim section 7, which extends around all four walls of the base section. The upper edge of the trim section includes an inwardly extending, substantially flat horizontal flange 8, the inner edges of which terminate substantially in alignment with the vertical plane of the walls 5 and 6.

Formed in the flanges 8 of the section 7 is a substantially continuous well, pocket or tunnel which, as shown in Figure 2, possesses in cross-section a substantially key stone formation, having a relatively restricted entrance slot 10 and a widened lower portion. As shown in Figure 5 the channel is provided with a transverse partition 11 adjacent to which there is provided a horizontally disposed inlet conduit 12, carrying a valve fitting 13 at its outer end. Also, on the other side of the partition 11 there is disposed an open ended outlet conduit 14, which serves as a telltale to denote when the channel 9 has been completely filled with a sealing compound, preferably a compound of a bituminous nature, which may be forced into the channel when heated so as to completely fill the latter but which will harden and solidify upon cooling. By providing the partition 11 between the conduits 12 and 14 the operator will be assured that the channel has been completely filled with the compound when the latter issues from the outer end of the conduit 14.

The cover section of the receptacle comprises in this instance a sheet metal body formed to include curved sides 15 and a transparent panel 16 in the top thereof, the bottom of the cover section being open, the lower edges of the sides 15 are, however, flared so as to seat upon the flange 8 on opposite sides of the slot 10 provided in connection with the channel 9. In the form of the invention disclosed in Figure 2 the lower edges of the sides 15 are provided with an integral depending web 17, which is adapted to be received within the channel 9 and has its extreme lower end provided with a relatively widened head 18 which, when embedded in the sealing compound, indicated at 19, will serve to hold the cover section in secured relation and relative position with the base section 2. In operation, it will be understood that the cover section is placed on the base section, with the web 17 positioned in the channel 9, as shown in Figure 2. A force pump or the like is then connected with the inlet conduit 12, or the fitting 13 of said conduit. By applying a pressure the sealing compound may then be forced completely around the channel 9 so as to completely fill all portions of the latter and to conform to the peculiar cross-sectional formation thereof. When said compound issues from the outlet conduit 14, due to the presence of the partition 11, the operator will be notified that the

space allotted for the reception of the sealing compound has been completely filled. The compound is then allowed to cool and harden, whereby due to the peculiar cross-sectional formation of the channel 9 and the web 17 a securing condition is established preventing undue separation of the two sections of the receptacle. Moreover, due to the presence of the sealing compound the interior of the receptacle will be, in effect, hermetically sealed, the elements excluded and the contents of the receptacle indefinitely preserved.

In Figure 3 a slightly modified form of the invention has been set forth wherein the upper edges of the cover section 3 are provided with inwardly extending horizontally disposed flanges 20, upon which is seated the transparent panel 16, the latter being held in secured engagement with the under portions of the flange 20 by a separable clip or strip 21, which is secured to the cover section by means of fastening elements 22. In Figure 4 an additional modified form of the invention has been set forth, wherein the web 17^a is integrally formed with the flange 8^a of the base section, and is received within a channel 23 provided in the cover section 3^a, the channel 23 registering with the channel provided in the flange 8^a. It is obvious that other modifications may be employed without departing from the principles of the invention as above set forth and I therefore do not limit myself to such structural details except as the latter are specifically set forth in the following claims.

What is claimed is:

1. In a receptacle of the class described, separable base and cover sections, one of said sections being provided, contiguous to the meeting portions of said sections, with a peripheral channel, a depending web provided upon the other of said sections and receivable within said channel, a single transverse partition wall in said channel and inlet and outlet conduits communicating with said channel to admit of the introduction of a bituminous sealing compound into all portions of said channel, said conduits being arranged adjacent to said partition.

2. In a receptacle of the class described, separable base and cover sections, one of said sections being provided, contiguous to the meeting portions of said sections, with a peripheral channel, a depending web provided upon the other of said sections and receivable within said channel, a single transverse partition wall in said channel and inlet and outlet conduits communicating with said channel to admit of the introduction of a bituminous sealing compound into all portions of said channel, said partition being arranged between said conduits.

3. In a receptacle of the class described, separable base and cover sections, one of said sections being provided, contiguous to the

meeting portions of said sections, with a peripheral channel, a depending web provided upon the other of said sections and receivable within said channel, a single transverse partition wall in said channel and inlet and outlet conduits communicating with said channel to admit of the introduction of a bituminous sealing compound into all portions of said channel, said partition being arranged between said conduits, and means formed within said inlet conduit for attaching a device for pouring the sealing compound into said channel.

5 In testimony whereof I affix my signature.

10 BERNICE EARL LAMBERT.
